R. F. DOHERTY.
CARPET.

No. 20,751.

Patented May 19, 1891.

UNITED STATES PATENT OFFICE.

ROBERT F. DOHERTY, OF YONKERS, NEW YORK, ASSIGNOR TO THE ALEX. SMITH & SONS CARPET COMPANY, OF SAME PLACE.

DESIGN FOR A CARPET.

SPECIFICATION forming part of Design No. 20,751, dated May 19, 1891.

Application filed April 22, 1891. Serial No. 390,044. Term of patent 3½ years.

To all whom it may concern:

Be it known that I, ROBERT F. DOHERTY, a subject of the Queen of Great Britain, residing at Yonkers, Westchester county, New York, have invented a new and original Design for Carpets, of which the following is a specification, reference being had to the accompanying photograph, which forms a part of the same.

- 10 The invention relates to a design to be worked into or upon surfaces, such as carpets or similar fabrics; and it consists in the novel configuration and grouping of figures herein specifically shown and claimed.
- 15 The accompanying photograph is a face view of a carpet, showing my new design. My design consists of the body A and the border B. The body A consists of an escutcheon surrounded by an intertwined regular spirally-arranged conventionalized leaf and flower-branch upon a shaded ground.
- 20

The border B consists of an escutcheon surrounded by an intertwined regular spirally-arranged conventionalized leaf and branch forms apparently supporting a vase containing flower forms upon a shaded ground, of an ornamented inner margin and of an outer shaded margin decorated with conventionalized flower and leaf forms.

What I claim, and desire to secure by Letters Patent, is—

- 1. The design for a carpet, consisting of the body A, substantially as shown.
- 2. The design for carpets, consisting of the border B, substantially as shown.
- 3. The design for carpets, consisting of the body A and the border B, substantially as shown.

ROBERT F. DOHERTY.
